US0D1054393S

(12) **United States Design Patent** (10) **Patent No.:** **US D1,054,393 S**
(45) **Date of Patent:** **** Dec. 17, 2024**

(54) **DISPLAY DEVICE FOR FURNITURE**

(71) Applicant: **LG DISPLAY CO., LTD.**, Seoul (KR)

(72) Inventors: **Chiyoung Lee**, Paju-si (KR); **Jeongeon Seong**, Paju-si (KR); **Soonmin Kwon**, Paju-si (KR); **Hyunjung Song**, Paju-si (KR); **Seokhyo Cho**, Paju-si (KR); **Jongyoung Park**, Paju-si (KR)

(73) Assignee: **LG DISPLAY CO., LTD.**, Seoul (KR)

(**) Term: **15 Years**

(21) Appl. No.: **29/766,873**

(22) Filed: **Jan. 19, 2021**

(30) **Foreign Application Priority Data**

Jul. 21, 2020 (KR) 30-2020-0033600

(57) **CLAIM**

The ornamental design for a display device for furniture as shown and described.

DESCRIPTION

FIG. 1 is a front, right perspective view of a display device for furniture showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing in the figures is for the purpose of illustrating portions of the display device for furniture and forms no part of the claimed design.

1 Claim, 7 Drawing Sheets
